UNITED STATES PATENT OFFICE.

MOSES CHAMPEN HAWKINS, OF EDINBOROUGH, PENNSYLVANIA.

TIME-LOCK.

SPECIFICATION forming part of Letters Patent No. 296,561, dated April 8, 1884.

Application filed July 28, 1883. (Model.)

To all whom it may concern:

Be it known that I, MOSES CHAMPEN HAWKINS, of Edinborough, in the county of Erie and State of Pennsylvania, have invented a new and Improved Time-Lock, of which the following is a full, clear, and exact description.

Figure 1 is a side elevation of my improved time-lock. Fig. 2 is an end elevation. Fig. 10 3 shows the center arbor and pinion, and Figs. 4 and 5 are respectively views of the center pinion and carrying-nut.

The object of this invention is to insure the release of the lock-bolt at the prescribed moment, and also to release the bolt in case of breakage of the spring of the time-movement.

The invention consists, mainly, in what I call an "accident-lever," provided with two pawls, one engaging a ratchet on the going-barrel, and the other engaging a stationary ratchet, the said lever being provided with an inclined surface for engaging the time-catch when the accident-lever is thrown forward by the recoil of the going-barrel on the breaking 25 of a spring.

In the drawings, in which the same letters of reference indicate the same parts in the different figures, A is the tumbler of an ordinary combination-lock; B, the sliding bolt, 30 having the usual projection, a, for entering the notch of the tumbler; and C is a latch turning on the pivot b, and capable of engaging the pin c, projecting from the side of the bolt B. The latch C is provided with the 35 short downwardly-projecting beveled arm d, and at the extremity of its free end there is a roller, e, on a pin projecting horizontally from the face of the latch. The time-movement D is provided with a pin-wheel, E, driven by a 40 pinion, f, on the end of the center arbor, F. The pin-wheel E has twelve equidistant screw-threaded holes near its periphery, into any one of which the pin g may be inserted. These holes correspond to the twelve hours marked 45 on the clock-dial, and the pin may be located in the wheel, so that it will engage the beveled surface of the arm d and raise the latch C, releasing the bolt B at any prescribed hour, thus 50 permitting of unlocking the combination-lock in the usual way.

Upon the arbor F is loosely placed a sleeve, h, between the ratchet-wheel i and the collar

j. The center wheel, k, is fixed to the end of the sleeve, and carries a spring-acted pawl, l, which engages the ratchet-wheel i.

On the sleeve h is loosely placed the center pinion, m, the said pinion being provided with a lug, n, which is engaged by a similar lug, o, on the nut p. The wheel G on the going-barrel H engages the pinion m, and also carries a ratchet-wheel, q, which is engaged by a 60 spring-acted pawl, r, carried by the arm I, which is fixed to a shaft, J, journaled in the frame of the time-movement D, and carrying upon its inner end the accident-lever K, the 65 upper end of which is inclined toward the pivot b of the latch C, and terminates in a hook, s. A fixed arm, L, having on its upper edge a series of ratchet-teeth, projects from 70 one side of the time-movement frame in position to engage the spring-acted hooked pawl t, carried by the arm K on the side opposite the pawl r.

In the normal working of the lock, the engagement of the pin g with the inclined face 75 of the arm d, projecting from the latch C, raises the said latch above the pin c at the prescribed time, so that the lock may be unlocked in the usual manner. In case the spring breaks I employ the recoil of the spring to 80 raise the latch C and liberate the bolt.

I have found by experience and investigation that in the great majority of cases the breakage of springs occurs in the inner coils. This being the case, the force of the recoil 85 comes mainly on the going barrel. The reverse motion of the going-barrel caused by the recoil of the spring carries forward the pawl r and the lever I, also the accident-lever K, when the inclined surface of the said accident-lever strikes the roller e on the latch C and raises the latch. At the same time the hooked pawl t engages the ratchet-teeth of the arm L, and retains the accident-lever and the latch C in a released position, so that the combination-lock can at any time thereafter be opened by 90 any one having the combination. Any effect of the recoil of the spring on the gearing of the time-movement is prevented by the free rotation of the pinion m on its sleeve in the 95 reverse direction for the greater portion of a revolution, and the subsequent unscrewing of the nut p when the lug n of the pinion m strikes the lug o of the nut p. The free retro-

grade revolution of the pinion *m* for the greater portion of a revolution permits the most of the force of the recoil to be exerted on the accident-lever, insuring its quick and certain action on the latch *C*.

The center arbor, *F*, is driven by the engagement of the pawl *l* on the wheel *k* with the ratchet-wheel *i*, fixed on the arbor. This arrangement admits of turning the arbor forward at any time for the purpose of adjustment.

I do not limit my invention to the precise form shown in the drawings, as it may be modified without departing from the spirit of my invention. For example, the pin *g* in the wheel *E* may be made adjustable in a circular slot in the wheel, instead of being placed in the different holes, and the pawls *r t* may be placed directly on the accident-lever instead 20 of the arm *I*.

I do not abandon or dedicate to the public any patentable feature set forth herein and not hereinafter claimed, but reserve the right to claim the same either in a reissue of any

patent that may be granted upon this application or in any other applications for Letters Patent I may make.

Having thus described my invention, I claim as new and desire to secure by Letters Patent—

1. The combination, with the slide-bolt *B*, having a side pin, *c*, of the latch *C*, engaging said pin, turning on a pivot, *b*, and having a downwardly-projecting beveled arm, *d*, and a roller, *e*, on a pin projecting horizontally from the face of the latch, a time-movement having 35 the pin-wheel *E*, the gear *f* *F*, and the pin *g*, whereby the latch may be raised and the bolt released at any desired time, as described.

2. The combination, with the going-barrel and time-catch, of an accident-lever, two spring-40 pawls on arms *I K*, a ratchet on the going-barrel, and a stationary ratchet, said lever having an inclined surface to engage with said time-catch, as and for the purpose specified.

MOSES CHAMPEN HAWKINS.
